UNITED STATES PATENT OFFICE.

C. W. SCHROEDER, OF NEW YORK, N. Y.

IMPROVED APPARATUS FOR DRYING DISHES.

Specification forming part of Letters Patent No. 59,083, dated October 23, 1866.

To all whom it may concern:

Be it known that I, C. W. SCHROEDER, of the city, county, and State of New York, have invented a new and Improved Apparatus for Drying Dishes, Plates, &c.; and I do hereby declare that the following is a full, clear, and exact description thereof, which will enable others skilled in the art to make and use the same, reference being had to the accompanying drawings, forming part of this specification, in which—

Figure 1 represents a sectional front elevation of this invention. Fig. 2 is a transverse vertical section of the same.

Similar letters of reference indicate like parts.

This invention relates to a box or stand, which is provided with one or more shelves to receive the dishes, plates, &c., to be dried, and with steam-pipes or other suitable heaters, in such a manner that dishes, plates, and other similar articles, when placed on said shelves after they have been washed, will dry rapidly by the action of the air, and the use of a towel for wiping such dishes, plates, &c., in order to get them dry can be dispensed with.

The ordinary method of drying dishes, plates, &c., after the same have been washed, is to wipe the same with towels of cotton or linen cloth, and as the towels become worn some of the fibers are liable to separate from their bodies and to adhere to the dishes, plates, &c., to the great detriment of the whole operation. This difficulty is avoided by the use of my drying box or stand A, which is provided with a series of shelves, a, that are so arranged that plates, dishes, &c., can be placed on them in an inclined position, as shown particularly in Fig. 1 of the drawings.

Two shelves extend parallel to each other

throughout the entire length of the box or stand, and between each pair of shelves extends a steam-pipe, b; or, instead of a steam-pipe, a heater, c, may be arranged between the shelves, said heater being filled with hot water or any other suitable heated material. The bottoms of the shelves are formed of a lattice-work, through which the water finds its way readily to the gutters d, and the plates and dishes are readily and quickly dried by the combined action of air and heat. The water which collects in the gutters d is conducted off through pipes e, and the dishes, plates, &c., when dried, are removed and put away, or they may be immediately used again. No towel or fibrous material comes in contact with the plates, dishes, or other articles, and consequently all danger of any fibers adhering to said dishes or other articles is avoided.

Any surplus space that may exist in the box or stand A can be used for the purpose of storing away the plates, dishes, &c., after the same have been dried; or, if desired, sugar, tea, coffee, or provisions of any kind may be stored up in said surplus space.

It is obvious that the box or stand can be made in a great many different forms, and I do not wish to confine myself to any particular form or shape.

Having thus described my invention, I claim as new and desire to secure by Letters Patent—

An apparatus for drying dishes, &c., composed of a box or stand provided with one or more sets of shelves and intermediate heaters, substantially as and for the purpose described.

C. W. SCHROEDER.
